UNITED STATES PATENT OFFICE.

CLARENCE T. EVANS, OF WAUWATOSA, WISCONSIN, ASSIGNOR TO THE CUTLER-HAMMER MFG. CO., OF MILWAUKEE, WISCONSIN, A CORPORATION OF WISCONSIN.

MOTOR CONTROLLER.

Application filed June 8, 1925, Serial No. 35,555. Renewed June 24, 1926.

This invention relates to motor controllers and is particularly applicable to compensator starters for induction motors.

My co-pending application, Serial No. 741,104, filed October 2, 1924, discloses a manually operated compensator starter including two movable contact elements, each having an extreme neutral position, all desired commutations of circuit, including opening thereof, being effected by movement of the elements each from one extreme position to another extreme position and release thereof.

The present invention has among its objects to provide a simple, efficient and reliable automatic compensator starter having operating characteristics of the aforementioned starter.

Another object is to provide an automatic compensator starter of the aforesaid character having improved means associated therewith for timing interruption of starting connections and establishment of running connections.

Various other objects and advantages of the invention will hereinafter appear.

The accompanying drawing schematically illustrates an embodiment of the invention which will now be described, it being understood that the embodiment illustrated is susceptible of modification without departing from the spirit and scope of the appended claims.

Referring to the drawing, the same illustrates a compensator starter of the character disclosed in the aforementioned application, the same being adapted to control a three-phase alternating current motor M and including movable contact elements 1 and 2, and a set of stationary contacts 3. Contact elements 1 and 2 are normally in the extreme positions shown in the drawing and are movable downwardly from such positions into opposite extreme positions. Contact element 1 in its opposite extreme position cooperates with the set of stationary contacts 3 to establish starting connections and contact element 2 in its opposite extreme position cooperates with contact element 1 upon return of the latter to its normal position to establish running connections. The running connections are interrupted by return of contact element 2 to normal position.

As set forth in the aforementioned appli-

cation, contact elements 1 and 2 are provided with operating shafts 4 and 5 respectively and element 1 is provided with five contact members 6 to 10, inclusive, while element 2 is provided with three contact members 11, 12 and 13. The set of stationary contacts 3 includes five contacts 14 to 18 inclusive each to cooperate with one of the contact members of element 1.

The aforescribed switch mechanism is adapted to establish starting and running connections for a polyphase motor M from a three phase circuit indicated by lines L¹, L² and L³. Lines L¹, L² and L³ are permanently connected to contact members 6, 8 and 10 respectively of contact element 1 and the contact members 6 and 10 are permanently connected to contact members 11 and 13 respectively of contact element 2, the terminals M¹ and M³ of the motor M are permanently connected to contact members 7 and 9 respectively of contact element 1, while the intermediate terminal M² of the motor is permanently connected to stationary contact 16 and also to contact member 12 of element 2. Stationary contacts 14 and 18 are connected to one terminal of compensator windings C¹ and C² respectively, and the opposite terminals of said windings are connected to terminal M² of the motor. Also, the compensator windings C¹ and C² are provided with intermediate taps connected to stationary contacts 15 and 17 respectively.

The electrical connections made between the supply circuit and the motor when contact element 1 of the starter is moved into engagement with the set of stationary contacts 3 and out of engagement with the set of stationary contacts 14 and 18 are apparent to those skilled in the art, and it is sufficient to state that in starting, the compensator winding C¹ is connected across phase L¹—L² while compensator winding C² is connected across phase L²—L³, and by reason of the connection of terminals M¹ and M³ of the motor to the intermediate taps of the compensator windings the motor will receive less than the full potential of the supply line. In the running position of the starter the terminals of the motor are directly connected to lines L¹, L² and L³ through engagement of the contacts of element 1 with the contacts of element 2 and

the motor will thus be supplied with full line potential.

Contact element 1 is moved downwardly from its normal position into its opposite extreme position by an electromagnetic winding 19 while contact element 2 is moved downwardly from its normal position into its opposite extreme position by an electromagnetic winding 20. The energizing circuit of winding 19 is controlled through the medium of a normally open push button 21 a normally closed push button 35 and two sets of auxiliary contacts, one including stationary contacts 22^a and 22^b and a normally open bridging contact 22^c and the other including stationary contacts 23^a and 23^b and a normally closed bridging contact 23^c. Contact 22^c is operatively connected to shaft 4 through the medium of an arm 24 and a rod 25 while contact 23^c is loosely mounted on the piston rod of a dash pot 27. The piston rod of dash pot 27 is connected to rod 25 by a spring 26 and said piston rod is provided with a shoulder for opening contact 23^c after a given upward movement of the dash pot piston.

Upon depression of push button 21, winding 19 is energized by a circuit extending from line L³ through push button 35 by conductor 28 through push button 21 conductors 29 and 30 through said winding, by conductor 31 through the normally closed auxiliary contact 23^c and by conductor 32 to line L². Immediately upon movement of contact element 1 into its starting position, auxiliary contact 22^c closes to maintain winding 19 energized by a circuit extending from line L³ through push button 35 by conductors 28 and 33 through auxiliary contact 22^c by conductors 34 and 30 through said winding by conductor 31 through contact 23^c and by conductor 32 to line L². After a predetermined interval determined by the setting of dash pot 27, switch 23 is opened to interrupt the aforescribed maintaining circuit for winding 19 and the contact element 1 then returns to normal position.

Immediately upon movement of contact element 1 into its starting position winding 20 is energized by a circuit extending from line L³ through a normally closed push button 35 through said winding and by conductor 36 to terminal M² of the motor. As set forth in the aforementioned copending application the contacts of switch member 8 are arranged to momentarily bridge stationary contact 16 and contact member 12 during the change over from starting to running and it is thus apparent that the aforescribed energizing circuit for winding 20 will be maintained during such change over. Thus, contact element 2 is moved out of its normal position into its opposite extreme position immediately upon establishment of starting connections and remains in this po-

sition to establish running connections upon return of the contact element 1 to normal position, as above described.

From the foregoing it is apparent that starting connections are established immediately upon depression of push button 21 and after a predetermined interval determined by the setting of dash pot 27 the starter acts automatically to interrupt the starting connections and establish running connections. The running connections are maintained by winding 20 subject to interruption under low voltage conditions in said winding or deenergization thereof by depression of push button 35.

What I claim as new and desire to secure by Letters Patent is:

1. In a motor controller, in combination, two contact elements each normally in a given extreme position and movable into an opposite extreme position, one of said elements in its opposite extreme position being adapted to establish starting connections, and the other being adapted in its opposite extreme position to cooperate with the former element in the normal position thereof to establish running connections, and an electromagnet associated with each of said elements for moving the same from its normal position into its opposite extreme position.

2. In a motor controller, in combination, two separately movable contact elements each normally in a given extreme position and movable into an opposite extreme position, a plurality of stationary contacts to be engaged by one of said elements in its opposite extreme position for establishment of starting connections, said element being adapted upon return to the normal position to cooperate with the other of said elements in the opposite extreme position thereof to establish running connections, an electromagnet associated with each of said elements for moving the same from its normal position into its opposite extreme position, and automatic means for deenergizing the electromagnet associated with said first mentioned element, after a predetermined interval upon movement of said first mentioned element into its opposite extreme position.

3. In a compensator starter for induction motors, in combination, a pair of electromagnets, contacts controlled by one of said electromagnets to establish and interrupt starting connections, and contacts controlled by the other of said electromagnets and adapted to cooperate with said former contacts to establish and interrupt running connections.

4. A compensator starter for induction motors, comprising a movable contact element, stationary contacts to be engaged thereby for establishment of starting connections, a second movable contact element to cooperate with the former contact element

- for establishment of running connections, separate electromagnets for operating said elements, and control means associated with the electromagnet of said first mentioned element for timing interruption of starting connections and establishment of running connections.
5. In a motor controller, in combination, two contact elements each normally in a given extreme position and movable to an opposite extreme position, one of said elements in its opposite extreme position being adapted to establish starting connections and the other in its opposite extreme position, being adapted to co-operate with the former element in the normal position thereof to establish running connections, an electromagnetic operating winding associated with each of said elements for moving the same into its opposite extreme position, and control means for the winding associated with said first mentioned element including means for establishing an energizing circuit for said winding and for interrupting such circuit after a predetermined interval.
6. In a motor controller, in combination, a set of stationary contacts, a contact element normally in a given extreme position and movable into an opposite extreme position to engage said stationary contacts for establishment of starting connections, a second set of movable contacts normally in a given extreme position and movable into an opposite extreme position to be engaged by said former element in the normal position thereof for establishment of running connections, an electromagnetic operating winding associated with said former element, means for establishing an energizing circuit for said winding and for interrupting the same after a predetermined period, and an electromagnetic operating winding associated with said latter element adapted to be energized upon establishment of starting connections and to be maintained energized during interruption of starting connections and establishment of running connections.
7. In a motor controller, in combination, two movable contact elements, each normally in a given extreme position and movable into an opposite extreme position, one of said contact elements being adapted in its opposite extreme position to establish starting connections, and the other being adapted in its opposite extreme position to cooperate with said former element in the normal position thereof to establish running connections, an electromagnetic winding for operating each of said elements, a switch for establishing an energizing circuit for the electromagnet associated with said former element, a switch for maintaining said energizing circuit upon opening of said former switch, and means including a dash pot for opening said last mentioned switch after a predetermined interval, following establishment of starting connections.
8. A compensator starter for induction motors, comprising cooperating contacts, certain being movable and being engageable and disengageable to establish and interrupt running connections and certain being stationary and being adapted to cooperate with certain of said movable contacts to establish starting connections, a plurality of electromagnetic windings each for controlling certain of said movable contacts and control means for said windings insuring establishment of starting connections upon energization of one of said windings and establishment of running connections upon deenergization of said former winding and energization of the other of said windings.
9. A compensator starter for induction motors, comprising cooperating contacts, certain being movable and being engageable and disengageable to establish and interrupt running connections and certain being stationary and being adapted to cooperate with certain of said movable contacts to establish starting connections, a plurality of electromagnetic windings each for controlling certain of said movable contacts, and control means for said windings insuring establishment of starting connections upon energization of one of said windings and establishment of running connections upon deenergization of said former winding and energization of the other of said windings, said control means including means for deenergizing said first mentioned winding after a given interval upon establishment of starting connections.
10. In a compensator starter for induction motors, in combination, a plurality of sets of contacts, certain of said sets being movable and certain being stationary, and control means for said sets of contacts comprising a plurality of electromagnetic operating windings providing for engagement of one of said sets of contacts by a second set of said contacts for establishment of starting connections and for engagement of a third set of said contacts by said second set for establishment of running connections.
11. In a compensator starter for induction motors, in combination, a movable contact element biased towards a given position and having an electromagnet associated therewith for moving the same to another position, stationary contacts to be engaged by said element in said last mentioned position to establish starting connections, contacts to be engaged by said element upon return movement thereof out of said last mentioned position for establishment of running connections and control means for said last mentioned contacts including a winding under the control of certain of said contacts.
12. A controlling device for electric cir-

cuits comprising stationary contacts, movable contacts, and means including a plurality of electromagnetic windings for moving some of said movable contacts in one direction to engage certain of said stationary contacts to make one set of circuit connections, for moving some of the engaged movable contacts in another direction to

disengage some of said engaged stationary contacts and to engage other movable contacts to make another set of circuit connections, and for disengaging all of said contacts. 10

In witness whereof, I have hereunto subscribed my name.
